SELF-OILING BURNISHING TOOL

William E. MacGuire and Kenneth J. Dodge,
Louisville, Ky., assignors, by mesne assign-
ments, to Frank B. Yingling, Hamilton, Ohio

Application May 18, 1944, Serial No. 536,220

7 Claims. (Cl. 29—90)

The present invention relates to burnishing tools and has for an object the provision of a device of this kind that is simple and compact, and affords a considerable saving in time during use.

Another object of the invention is to provide a device of this kind with a self contained means for containing lubricant and a manually operated means to selectively supply lubricant therefrom to the working end or tip of the tool.

Still another object of the invention is to provide a tool of this character having interchangeable working tips that are easily connected to or removed from the remainder of the tool without loss of lubricant from the self contained supply.

A further object of the invention is to provide a burnishing tool that is particularly advantageous in use upon large objects such as the skin of metal airplanes, where the worker has heretofore lost much valuable time while employing the old familiar method of burnishing away the blemishes on the metal in places that are not freely accessible.

These and other objects are attained by the means described herein and disclosed in the accompanying drawing, in which:

Fig. 1 is a longitudinal sectional view showing a preferred embodiment of the invention, part being broken away.

Fig. 2 is an elevational view of an interchangeable burnisher tip for the device of Fig. 1.

Fig. 3 is a top plan view of the device of Fig. 2.

Fig. 4 is an elevational view of another interchangeable burnisher tip for the device of Fig. 1.

Fig. 5 is a top plan view of the device of Fig. 4.

Heretofore the hand burnishing of metal products to remove scratches, blemishes and the like has been carried out by placing a drop of oil or other lubricant on the work or on the properly shaped end of a smoothly ground tool. The points or tips of the tools were formed in a variety of shapes and the operator customarily selects the shape best adapted to the contour of the part upon which he is working at a particular time. The operator would also have with him an oil can for applying lubricant as required. In the large scale production of products which require burnishing, much time is lost by those engaged in the hand burnishing operations. The operator frequently does not select all of the differently shaped burnishing tools that he may require and must, in that event return to the tool crib for additional tools. Furthermore the separate handling of the oil can becomes a nuisance and a source of lost time, especially when it becomes lost, or drops to some inaccessible place. In the construction of

metal aircraft, these time losses assume excessive proportions, particularly when the burnishing hands are required to work on the various parts of large aircraft, and they frequently lose or drop the oil can while working at considerable elevation above the floor so that they are tempted and frequently do neglect to use a suitable amount of lubricant in polishing the blemishes from the metal skin of the craft.

By means of the present invention all these various time losses are completely eliminated in as much as the operator may withdraw from the tool crib a single tool having a plurality of interchangeable burnishing tips and having moreover a self-contained and selectively releasable supply of oil.

Reference is made to the drawing, particularly to Fig. 1 which illustrates a preferred embodiment of the self oiling burnishing tool of the invention. The tool of the invention comprises a tubular shank 8 which is threaded at the handle end 9 and at the tip end 10. The bore of shank 8 at the tip end has a ground valve seat 11 for seating a valve 12 secured on an elongated stem 13. The stem has thereon a circular washer 14. A handle 15 may be made of any suitable rigid material, preferably a transparent synthetic plastic. The handle may be round and the enlarged portion thereof comprises an oil chamber 16. The reduced end 17 of the handle is interiorly threaded for a distance to receive the threads 9 of the tool shank 8. A lock nut 18 is also carried by the threaded shank 8 and serves to securely bind the shank in the reduced end of the handle. The reduced end 17 of the handle also has a bore 19 in which there is seated a coil spring 20 which abuts the end of shank 8 and one face of the washer 14 on the valve stem. By this arrangement the valve 12 is spring retained in a closed position. When the valve stem is depressed, valve 12 opens and the washer 14 acts as a pump to assure the flow of a measured quantity of oil which is below the washer 14 while the washer, in entering the reduced bore 19 prevents the uncontrolled flow of oil from the reservoir or oil chamber 16. At the top of handle 15 there is an interior thread 21 to receive the reduced threaded and shouldered end 22 of a cap 23. Cap 23 has an enlarged recess or counter-bore 24 and a central tapered bore 25. A tapered button member 26 passes through the bore 25 and the top of the button is arranged so as to at all times lie beneath the end of the cap. The cap has an interiorly threaded bore 27 for the reception of the threaded stud 28 which holds an oil seal felt washer 29 snugly against the button so that the hollow interior of cap 23 is sealed

against leakage of oil from the chamber 16. The stud 28 has a bore 30 extending partly therethrough for freely receiving the end of valve stem 13.

The exterior thread 31 at the free end of the tubular shank 8 is adapted to receive a burnishing tip 32 of any selected style, said tip 32 being desirably of the same diameter as the tubular shank 8. Tip 32 has a bore 33 which is internally threaded for the reception of thread 31, said bore being extended sufficiently to permit the valve 12 to be moved from its seat. Tip 32 has a transverse bore 34 and an axial bore 35 which provides communication between the bores 33 and 34. That portion of the wall of bore 35 nearest the points is slightly ground away as at 36 so as to insure the flow of released oil onto the tip of the tool where it is needed.

In Figs. 2 and 3 there is separately illustrated an interchangeable burnishing tip of the so-called generally triangular shape, this tip being indicated at 320, the transverse bore 340 and the break or ground away portion being indicated at 360.

In Figs. 4 and 5 an interchangeable tip of the so-called half-round shape is indicated at 3200.

In use, the tool normally has the valve 12 closed under the influence of spring 20 and the chamber 16 containing oil is closed by the cap and the oil seal felt 29. The tool would be issued from the tool crib with a variety of the small tips such as 32, 320, 3200, and possibly a number of other shaped tips. A section of a drill rod (not shown) of a diameter to be accommodated in the bore 34 of the tip serves as a wrench for use in the attachment and detachment of the interchangeable tips. The entire tool with a plurality of differently shaped burnishing tips forms a very compact arrangement that can be carried in the tool pocket of the worker who is thus relieved of the necessity of carrying an oil can in climbing about scaffolding and the like while burnishing the various blemishes which must be sought for and removed as the operator progressively assumes the work. If the contour of the surface to be burnished requires a differently shaped tool, the operator merely substitutes a selected one without leaving the work, then depresses the button 26 slightly with the thumb to release a small amount of oil which flows onto the working surface of the newly substituted tip.

In filling the chamber 16 with oil, the cap 23, which may have a knurled edge, is unscrewed and the button structure 26 remains frictionally attached through the agency of the felt washer. The piston rod remains in place and under the influence of spring 20 so that valve 12 remains closed during the filling operation.

From the foregoing the advantages as well as the care and operation of the tool will be readily understood. It is to be understood furthermore that the device of the invention may be subject to limited variation in structural detail within the spirit of the invention and the scope of the appended claims.

What is claimed is:

1. A self oiling burnishing tool comprising a hollow shank, a hollow handle on said shank and having its interior in communication with the interior of said shank, a cap for the end of said handle, a valve for closing the free end of said shank, a valve stem attached to the valve and extending through the shank and said handle, a burnishing tip member removably mounted on

the free end of the shank and having an axial bore for communication with the hollow shank when the valve is open, and a transverse bore connecting with the axial bore, and means manually operable from the exterior of the handle and for opening said valve.

2. In a self oiling burnishing tool the combination of a hollow handle and shank structure for containing oil, a valve normally closing the free end of the shank, a cap including a relatively removable finger piece for closing the end of the handle, a valve stem connected to the valve and extended through the shank and handle and into the finger piece in the cap, yieldable means for retaining the valve in a normally closed position and yieldingly resisting manual depression of the finger piece in the cap and a burnishing tip removably secured on the free end of the shank and having passageways for providing communication between the exterior surface of said tip and a hollow interior of the shank.

3. A self oiling burnishing tool comprising a hollow handle, a hollow shank attached to the handle and having open communication with the interior thereof, a valve stem extending through the handle and shank, said handle having an axial bore of reduced diameter, a spring surrounding the valve stem and disposed in said reduced bore in said handle and abutting the inserted end of said shank, a fixed plunger washer on the valve stem and forming an abutment for the spring whereby the washer plunger normally provides open communication through the handle and shank, means for closing the handle and leak proof means carried by the last mentioned means for manually depressing the valve stem and entering the plunger washer into the restricted bore in the handle for closing communication between the handle and said bore.

4. In a self-oiling burnishing tool the combination with a hollow shank adapted for the controlled passage of oil therethrough, threads on the free end of said shank, and an interchangeable tip member having an axial bore, threads in said bore for removably mounting the tip on the threaded end of said hollow shank, the opposite free end of said tip member having a predetermined shape for burnishing operations, said tip having a transverse bore therein communicating intermediate its ends with the lower end of the axial bore, the wall of the transverse bore in said tip being cut away on the side opposite its point of communication with the axial bore whereby oil passing through the axial bore is flowed onto the working surface of the tip.

5. An interchangeable tip for a self oiling burnishing tool comprising an elongated member having an axial bore at one end, means on said end for attaching said tip to a hollow shank, the other end of said tip having a predetermined shape for selected burnishing operations, said tip being provided intermediate its ends with a transverse bore in constant communication with the axial bore, the wall of which transverse bore is cut away at at least one end to form a shallow directional oil channel extending toward the working end of said tip.

6. An interchangeable tip for a self oiling burnishing tool comprising an elongated body having an axial bore extending partly therethrough and a transverse bore communicating therewith, the opposite end of said elongated body being suitably shaped for selected burnishing operations and provided with shallow surface ways affording free

flow of oil from the ends of the transverse bore onto the working surface of said shape of predetermined form.

7. In a hand burnishing tool the combination of a hollow handle and a shank structure for receiving a supply of oil, the end of the shank being exteriorly threaded and interiorly developed into a valve seat, a removable burnishing tip body having a hollow interiorly threaded end for mounting on the threaded end of said shank, said tip having a transverse bore and a restricted axial

10 bore communicating therewith and with said hollow end, the surface of said tip provided with shallow cut-away portions communicating with the ends of the transverse bore in the tip for directionally distributing oil from said transverse bore toward the work end of said removable tip, and a valve member yieldably retained on the seat in the end of the shank.
